UNITED STATES PATENT OFFICE.

WILLIAM S. SCALES, OF BOSTON, MASSACHUSETTS, ASSIGNOR TO HENRIETTA W. DOBLE, OF QUINCY, MASSACHUSETTS.

GLUING MECHANISM FOR PAPER BOXES.

SPECIFICATION forming part of Letters Patent No. 732,225, dated June 30, 1903.

Application filed February 2, 1903. Serial No. 141,406. (No model.)

To all whom it may concern:

Be it known that I, WILLIAM S. SCALES, a citizen of the United States, and a resident of Boston, in the county of Suffolk and State of Massachusetts, have invented certain new and useful Improvements in Gluing Mechanisms for Paper Boxes and the Like, of which the following is a specification.

The invention relates to an improvement in 10 gluing mechanism for cartons or paper boxes, bags, and the like.

One feature of the invention relates to the means for securing a rectilinear movement of the glue-roll across the part which is to be glued.

Another feature of the invention relates to means by which if the machine goes through its movements without any carton in position on the holder or forming-block the glue-roll 20 will be prevented from coming in contact with the forming-block.

The invention will now be fully described by reference to the accompanying drawings, and the novel features thereof will be particularly pointed out in the claims at the close 25 of the specification.

The drawings represent the invention as applied to a machine for setting up cartons having an intermittently-rotating head with 30 spider-arms, from which are suspended forming-blocks on which the cartons are held during the several operations.

In the drawings, Figure 1 is a plan view showing the spider and Geneva stop-motion 35 and mechanism for actuating the glue-roll and latch, showing the throw-out mechanism for the latch in the position assumed after one of the blocks has passed the fingers 232 and 238 with a carton thereon, the latch being 40 thrown out. Fig. 2 is a plan view similar to Fig. 1, showing the throw-out mechanism for the latch in the position in which it is left after the passage of the block without a carton, the latch being thrown in. Fig. 3 is a 45 side elevation looking toward the left in Fig. 1, showing the cam for actuating the glue-roll and cam for giving the straight-line motion to the glue-roll, said cam being in its upward position with the latch thrown out and the 50 glue-roll engaged with the under surface of the carton-flap. Fig. 4 is an enlarged detail

side elevation of the glue-roll mechanism, showing the cam for giving straight-line motion to the glue-roll latched in its lowermost position and causing the glue-roll to clear the 55 under surface of the block.

In the machine shown in the drawings there is represented a rotary head or spider mounted on a rotary shaft 1 and having a series of radiating arms 2, each of which carries pend- 60 ent therefrom a carton holding or forming block 6, on which the cartons are held while the flaps are being glued. The head is given an intermittent rotary movement by any suitable mechanism, turning at each period of 65 movement through an arc sufficient to bring the blocks 6 in successive rotation into position for the gluing action. The mechanism shown in the drawings for giving this intermittent motion to the head is a form of Geneva stop-motion.

Mounted on shaft 1 is a slotted disk 8. Mounted on rotary shaft 74 is a disk 7, having a spur 9, which carries a pin 10, adapted to engage at each rotation with one of the slots 3 75 in disk 8 and turn the head, with the forming-blocks 6, through a certain arc.

Mounted on shaft 4, which is journaled in the forked arms of lever 105, is a rotary glue-roll 63, which has a reciprocatory movement 80 beneath the lower end of the carton-block 6 at certain times in the operation of the machine to apply glue to the carton-flaps, provided a carton is on the block, and after each reciprocation it engages with a glue-feed roll 85 123, which is supplied with glue from a glue-pan 124.

The mechanism for actuating the glue-roll is as follows: Lever 105 is fulcrumed on a pivot 5, projecting from an arm 211, pivoted at 90 212 to the fixed support 213. Pivoted at 218 to the fixed support 213 is a bell-crank lever 219, one arm of which is connected by link 220 with the lever 105 and the other arm of which is connected by rod 221 with 95 one end of lever 222, fulcrumed at 223. The other end of lever 222 has a cam-roll 224, which engages with a cam 225 on shaft 27, and through the connections described lever 219 is actuated to oscillate the lever 105 and 100 reciprocate the glue-roll 63. It is obvious that if the pivot 5 were fixed the glue-roll 63

would move only in the arc of a circle. Arm 211, however, to which lever 105 is pivoted, is itself pivoted at both ends, and the pivot 5 forms a movable fulcrum for lever 105. 5 Carried on the lower end of lever 105 is a roller 214, which moves in a cam-path 215 in the cam 216. The cam-path is so formed that when the cam 216 is in the position shown in Fig. 3 and the lever 105 is actuated by the rotation of the cam 225 the tendency of the upper end of the lever and of the glue-roll to describe an arc of a circle will be compensated by the movement of the lower end during a part of its stroke, and the resultant motion will be in a straight line during that portion of its movement where the glue-roll passes under the block 6 and its attached carton 260.

It is not important to have the glue-roll 20 move in a straight line except where it passes in engagement with the carton-flap on the block. It is rather desirable that it should move out of its straight-line path at the end of its stroke, so as to be out of the path of 25 the carton and block during the rotation of the spider-head. The dotted line 217 217 shows the path described by the center of the glue-roll.

The parts are so adjusted that when the 30 cam 216 is in the position shown in Fig. 3 the rectilinear path of the glue-roll 63 when it passes beneath the carton-block 6 will be at the right height for the glue-roll to contact with the carton-flaps and apply the 35 glue. It is desirable, however, to provide means by which if the block 6 has no carton upon it the glue-roll shall not rub across the lower end of the block, because such engagement will leave a film of glue on the 40 block, which will be objectionable and will cause the carton to stick to the block the next time around when a carton is placed upon it. In order to provide for this, the cam 216 is made movable, and mechanisms are provided 45 by which the said cam will be automatically locked in the position shown in Fig. 3 if a carton is on the block and by which if a carton is not on the block the said cam will be lowered and locked in its lower position 50 during the reciprocation of the glue-roll, so that the glue-roll will not engage with the block. The mechanisms for accomplishing this are as follows: One end of cam 216 is pivoted at 248 to the fixed arm 213. The 55 cam may be turned up and down on its pivot. Two stop-pins 249 and 250 limit the up-and-down movement. The unpivoted end of the cam 216 rests on a finger 251, pivoted at 252 to the fixed support 213 and is normally held 60 by a spring 253 in a position to retain the cam 216 in its uppermost position, as shown in Fig. 3. A shoulder 254 prevents the spring from throwing the finger 251 too far over. Rising from the table 31 is a column 226, 65 having a long bearing 227, which forms a journal for a tubular shaft 228. Fast to or integral with the tubular shaft 228 is a finger

232, which projects into the path of the carton-block 6 and is engaged thereby each time the spider makes a turn through the arc of 70 movement to bring the block and carton into position for gluing. (See Fig. 1.) Rising from the table 31 is another column 233, having a long bearing 234, which forms a journal for a tubular shaft 235. Said shaft is 75 supported in a manner similar to shaft 228. Fast to or integral with tubular shaft 235 is a finger 238, which intersects the cylindrical plane in which the carton-block 6 moves. It is, however, below the block far enough so 80 that it does not intercept the block, but is high enough to be engaged by the depending flap 60 of the carton 260 if a carton is on the block. Fast to or integral with the tubular shaft 228 is an arm 239, to the other end of 85 which is pivoted one end of a connecting-rod 240. The other end of said connecting-rod is pivoted to one end of an arm 241, which is fast to or integral with tubular shaft 235. Fast to or integral with tubular shaft 235 is 90 an arm 242, to which is pivoted one end of a connecting-rod 243, the other end of said connecting-rod being pivoted to a link 244, which is pivoted to a hook-lever 245, having a hook-catch 246. Said lever 245 is pivoted 95 at 247 to the fixed support 213. Projecting from bell-crank lever 219 is a finger 255, which when the said lever is rocked by the cam 225 through the connecting mechanism in a direction to move the glue-roll 63 toward the glue-feed roll 123, as shown in Fig. 4, will engage finger 251, on which rests lever 216, and will turn it down out of engagement with said cam, compressing spring 253. A cam finger or boss 256, also projecting from 105 bell-crank 219, will engage with a stud 257, which projects from the side of cam 216, and cause the cam 216 to be turned down on its pivot. This movement will occur while the spider-head is moving through its arc of movement. When the spider-head moves, the block 6 engages during its course the finger 232 and partially turns the tubular shaft 228 on its journal, and through the connections already described it also turns shaft 235, thereby 110 moving connecting-rod 243 in a direction to cause the hook-latch 246 to hook over onto the upper side of a projecting shoulder 258 on the rear end of cam 216 and hold the cam in its lowermost position, resting on the stop 250, as shown in Fig. 4, and unless the latch 246 is in some way tripped before the glue-roll 115 passes back under the carton-block the lever 105 will not reach high enough to cause the glue-roll to come in contact with the block. 120 This condition is shown by the dotted lines in Fig. 4.

Mechanism is provided by which the latch will be tripped only when a carton is on the block. The outside corner of the downwardly-projecting flaps at the lower end of the advance side of the carton-block will engage the finger 238 after the finger 232 has caused the latch to engage the cam 216 and will cause 130

tubular shaft 235 to turn in the reverse direction to its former turning and through the connecting mechanism will release the latch 246 from the cam 216. It will also through the 5 connecting mechanism turn tubular shaft 228 back again and bring finger 232 into position to be engaged by the next following block 6 at the next movement of the spider-head.

When the lever 105 turns so as to carry the 10 glue-roll from the feed-roll, as shown in Fig. 4, back under the carton-block 6, the bell-crank 219 will be turned back and the finger 256 will be withdrawn from the stud 257, and the finger 255 will be withdrawn from the piv- 15 oted cam-supporting finger 251, and the spring 253 will turn said supporting-finger 251 upon its pivot into engagement with the under side of cam 216. If the latch 258 has been released by a carton on the block, the said 20 finger 251 will lift the cam 216 up into its normal position, so that the fulcrum of lever 105 will be raised high enough for the glue-roll to pass in contact with the carton-flap. If a carton is not on the block so as to re- 25 lease the latch 246, the spring 253 will not be able to turn back the finger 251 its full distance and the cam 216 will remain thus latched until a block does come around with a carton thereon and engage the finger 238 to 30 trip the latch.

Mechanism for folding the flaps is not shown herein, as that does not form a part of the present application. They may be folded in any suitable way either automatically or 35 by hand.

Shaft 27, on which the glue-roll-actuating cam 225 is mounted, is connected by bevel-gear 144 with bevel-gear 141 on shaft 74, which carries the driving spur-disk 7, so as to pro- 40 duce harmony of movement. (See Fig. 3.)

What I claim is—

1. In combination with a carton-forming block, and mechanism for moving said block intermittently, a glue-roll, mechanism for reciprocating said glue-roll beneath the said block, when the block is at rest, and mechanism controlled by a carton on the block to cause the glue-roll to pass in contact with a flap of said carton, substantially as described. 45

2. In combination with a carton-forming block and mechanism for moving said block intermittently, a glue-roll, mechanism for reciprocating said glue-roll beneath said block when the block is at rest, mechanism controlled by a carton on the block to cause the glue-roll during its movement to engage the surface of a folded flap of said carton, and mechanism which holds the glue-roll out of contact with the carton-block if there is no 55 carton on the block, substantially as described.

3. In combination with a carton-forming block and mechanism for moving said block intermittently, a glue-roll, mechanism for reciprocating said glue-roll beneath said block when the block is in a position of rest, mech- 60

anism actuated by the moving block before it arrives at the gluing-point to so adjust the glue-roll-actuating mechanism that unless re-adjusted the glue-roll will not make contact 70 with said block, and mechanism actuated by a carton on the moving block to readjust the glue-roll-actuating mechanism so that the glue-roll during its reciprocation will engage with a folded carton-flap, substantially as de- 75 scribed.

4. In combination with a carton-forming block, and mechanism for moving said block intermittently, a glue-roll mounted on a pivoted lever, a movable fulcrum for said lever, 80 mechanism for oscillating said lever on its fulcrum, mechanism for moving said fulcrum during the oscillation of the said lever in such manner as to cause the glue-roll during a part of its course to move in a rectilinear 85 path, and mechanism actuated by a carton on the moving block to cause the glue-roll to move in a different path from that in which it will move when there is no carton on the block, substantially as described. 90

5. In combination with a glue-roll mounted on a pivoted lever, a movable pivot for said lever intermediate its ends, mechanism for oscillating said lever, a cam which controls the direction of movement of said pivot 95 and causes the glue-roll to move in a rectilinear path during a part of its course, a carton-holding block, mechanism for moving said block into a position over the path of movement of the glue-roll, mechanism actuated by the moving block to cause said cam to be moved into such position as to cause the glue-roll to move in a path which will not carry it into engagement with the carton-block unless the position of the cam is again 105 changed, and mechanism actuated by a carton on the moving block to restore said cam to a position where it will cause the glue-roll to move in a path which will carry it into engagement with a folded flap of the carton, 110 substantially as described.

6. In combination with a glue-roll mounted on a pivoted lever, a movable pivot for said lever, mechanism for oscillating said lever, a cam which controls the direction of movement of said pivot and causes the glue-roll to move in a rectilinear path during a part of its course, a carton-holding block, mechanism for moving said block into a position over the path of movement of the glue-roll, said cam being pivoted at one end and having a movable support which normally holds the cam in a position which would cause the glue-roll to move across the folded flap of a carton on the block, mechanism actuated by the moving of the block to trip said support, mechanism which causes the cam to change its position and a latch which locks the cam in its changed position to change the path of the glue-roll, mechanism actuated by 120 a carton on the moving block to trip said latch, and mechanism which returns said cam- 125

support and cam into position for causing the glue-roll to engage with the carton-flap, substantially as described.

7. In combination, an oscillating lever, a cam with which one end of said lever engages, a rocking bell-crank lever, a link connection between said two levers, mechanism for rocking said bell-crank lever, and oscillating said first-described lever, the form of the cam being such as to cause the free end of the said oscillating lever to move during a part of its course in a rectilinear path, substantially as described.

8. In combination with a rotary head, a series of carton-holding blocks carried thereby, mechanism for rotating said head, a gluing device mounted on an oscillating lever, mechanism for oscillating the lever and moving said gluing device beneath one of said blocks, a cam which is engaged by said lever and causes the fulcrum to shift during the oscillation in such manner as to cause the gluing device to move in a rectilinear path under said block, mechanism which moves said cam into a position which if not disturbed will cause the gluing device to move in a path which will not bring it into contact with the block, a swivel-shaft having a finger which projects into the path of said blocks and when engaged by a block turns said swivel-shaft, a second swivel-shaft having a crank-and-link connection with said first swivel-shaft and having a finger thereon which when the first-described swivel-shaft is turned by the block turns said second finger into the path of a carton-flap when there is a carton on said block, mechanism actuated by the cam-actuating mechanism to move said cam and hold it in a new position, a latch actuated by the turning of said shafts to hold said cam in its new position, the engagement of said carton-

flap with the finger on said second swivel-shaft causing it to turn in the reverse direction and release the latch, and mechanism which moves the said cam back into position where the gluing device will move in contact with the carton-flap, substantially as described.

9. In combination, an oscillating lever, a movable fulcrum for said lever intermediate its ends, a gluing device mounted on one end of said lever, a pivoted cam which engages with the other end of said lever and which when the lever oscillates causes the gluing device to move in a curved path at each end of its course and in a straight path in the intermediate part of its course, a rocking lever having a link connection with said oscillating lever, driving mechanism connected with said rocking lever which actuates thereby the said oscillating lever, a pivoted lever which normally engages said pivoted cam and holds it in a certain position, a finger on said rocking lever which when the said lever rocks in one direction disengages said pivoted support and turns it back, a spring which engages said support and is compressed by the turning back of said support, a second finger on said rocking lever which turns said cam on its pivot and causes the gluing device to move in a different path, said spring turning the said pivoted support again into engagement with said pivoted cam and moving the cam back to its normal position when the rocking lever turns in a direction to retract its fingers, substantially as described.

In testimony whereof I have affixed my signature in presence of two witnesses.

WILLIAM S. SCALES.
